D. A. KEATING ET AL

PICKER STICK

Filed June 19, 1924

UNITED STATES PATENT OFFICE.

DANIEL A. KEATING, OF BRIDGEPORT, AND JAMES B. TATEM, OF PUTNAM, CONNECTICUT, ASSIGNORS OF ONE-HALF TO THE AMERICAN TUBE & STAMPING COMPANY, OF BRIDGEPORT, CONNECTICUT, A CORPORATION OF CONNECTICUT, AND ONE-HALF TO JAMES B. TATEM, DOING BUSINESS AS JAMES B. TATEM & SON, OF PUTNAM, CONNECTICUT.

PICKER STICK.

Application filed June 19, 1924. Serial No. 720,954.

To all whom it may concern:

Be it known that we, DANIEL A. KEATING and JAMES B. TATEM, citizens of the United States, residing at Bridgeport and Putnam, respectively, in the counties of Fairfield and Windham, respectively, and State of Connecticut, have invented certain new and useful Improvements in Picker Sticks, of which the following is a specification.

10 This invention relates to an improved construction of combination wood and metal picker stick of the type employed to drive the shuttle across a loom; and the object of this invention is the provision of a picker stick of this character having its upper end portion of wood and its lower end portion of metal, the metal being primarily for the purpose of strengthening that portion of the stick which ordinarily breaks first, while the upper or wooden portion is for the purpose of providing the flexibility required in a picker stick.

A further object of this invention is to provide the lower portion of the stick of metal formed into channel shape, the upper end of this metal portion being shaped to receive the lower end of the wooden upper portion and support its front and rear edges against the hammering shocks of the shuttle.

The invention further consists in the provision of a stiffening member applied to the lower end of the metal portion for the purpose of providing a proper bearing for the pivot pin when the stick is designed to be oscillated on a pivot or bolt. One of the forms of this construction is set forth and claimed in our copending application No. 758,337.

40 With these and other objects in view, the invention consists of certain novel features of construction, as will be more fully described, and particularly pointed out in the appended claims.

45 In the accompanying drawings:

Figure 1 is a side elevation showing our improved construction of picker stick, the upper portion being wood and the lower portion metal in channel form.

50 Figure 2 is a side elevation of our improved construction of picker stick.

Figure 3 is an enlarged sectional end view of the pivoted end of the stick on line 3—3 of Figure 1.

Figure 4 is a sectional end view of the 55 stick on line 4—4 of Figure 1.

Figure 5 is a perspective view of a short length of a channel-shaped member which is designed to be inserted into the lower end of the metal portion of the picker 60 stick.

Figure 6 is a modified construction of picker stick showing a blank having an extending end portion from which the lower end of the metal portion of the stick may 65 be formed.

Figure 7 is a sectional side elevation of the lower end of a picker stick showing the extending portion of the blank as folded to form a short length of opposite cooperating side bearing wall at the lower end of the stick.

Figure 8 is an enlarged sectional end elevation on line 8—8 of Figure 7.

Figure 9 is another modification illustrating a filler piece of wood or the like inserted into the channel at the lower end of the stick to provide a bearing for the pivot pin.

It is found in the practical construction and operation of picker sticks that, when made entirely of wood, their operating life, owing to the severe hammering strains to which they are subjected, is very short, and it is also found of advantage to strengthen 85 the lower portion of the picker stick to prevent excessively rapid deterioration. It is also found necessary in the construction of picker sticks to provide a certain degree of resiliency which has heretofore 90 been found in the usual picker stick of hickory. Therefore, in order to obtain, at once, the required strength and also the yieldability, we have formed a picker stick having its upper portion of wood where the 95 greatest resiliency is required, and its lower portion of metal where its greatest strength is required. By this construction, when one portion of the stick is destroyed a fresh part may replace the broken one 100 and connected to the unbroken portion; and the following is a detailed description of

one embodiment of our invention by which these advantageous results may be obtained:

With reference to the drawings, 10 designates the upper portion of our improved construction of picker stick which is formed of wood, usually of hickory, the same being preferably rectangular in cross section, larger at its lower end 11 and tapering 10 towards its upper end 12.

This wooden portion is preferably formed of a length substantially one half of the entire stick, but we do not wish to be limited to any particular proportions as its length 15 may be of any desired proportion of the whole length of the stick. The lower portion of our improved picker stick is herein shown as being in channel form as at 13, the body portion of the channel being preferably open. This channel-shaped member 20 may be formed in any desired manner, of any desired material and of any desired shape in cross section, but we preferably form the same of sheet metal and fold this 25 metal to provide one side wall 14, a rear wall or flange 15, and a front wall or flange 16.

The upper end of this channel member is 30 preferably formed to receive and fit the lower end 11 of the wood and the front and rear walls 15 and 16, respectively, are arranged to provide a substantial backing to both the front and rear edges of the wood to support the same while acting upon the 35 stick. This stick is preferably secured in the upper end of the channel member by means of bolts or rivets 17.

When this picker stick is designed to be 40 mounted upon a pivot pin, we preferably reinforce its lower end in various ways to receive and support the pivot pin on which it is designed to oscillate. In some instances, we provide a short section of channel member 18, as illustrated in Figure 5, 45 and insert this with its flanges 19 set in between the front and rear edges 15 and 16 of the main channel member, and we also pierce the side plate 20 of this member and the side plate 14 of the main channel 50 member to form cooperative bearing openings 21 and preferably force the stock about the hole inwardly as at 22, to provide an extending bearing surface for the pin. This short section of channel member 18 55 may be secured by any suitable means in the main channel member but we preferably spot weld the same as at 23 through the adjacent edge or flange portions thereof.

Another construction by which this additional bearing portion may be formed on the 60 lower end of the main channel member is, as illustrated in Figures 6, 7, and 8, which is that of providing an elongated integral tongue member 24 on the end of the side 65 wall 14 and fold this tongue member first

laterally to provide an end wall 25 and then upwardly to provide an opposite wall 26 which portion is adapted to set in between the front and rear edge walls 27 and 28 of the main channel member and these side 70 walls 14 and 26 are then pierced as at 29 and the stock about the piercing turned inwardly as at 30 to provide extending bearings for the pivot pin.

In still other cases, as illustrated in Figure 75 9, a block of wood such as lignum vitæ, or the like, may be inserted between the front and rear edge walls 15 and 16 of the channel member through which a hole 30 is formed to receive the pivot pin on which the stick is designed to oscillate.

We do not wish to be limited to mounting our improved picker stick to oscillate upon a pivot pin as other suitable means for supporting the lower end may be employed.

A picker stick of our improved construction is very simple and practical to manufacture, is effective in its operation and its working life over that of the usual all-wood picker stick is greatly extended and at the 20 same time it provides the required resiliency for receiving the shocks and effecting the throw of the shuttle.

The foregoing description is directed solely towards the construction illustrated, 95 but we desire it to be understood that we reserve the privilege of resorting to all the mechanical changes to which the device is susceptible, the invention being defined and limited only by the terms of the appended 100 claims.

We claim:

1. A picker stick having substantially its upper half of wood and substantially its lower half of a single piece of metal channel form in cross section with yieldable edge walls, the lower end of the wood extending but a short distance into the upper end of the channel and pressure exerting fastening members extending through the opposite edge walls of the channel causing said walls to spring inwardly and bind the wooden end between them, the lower end of the metal portion being provided with spaced apart oppositely disposed side walls and edge 110 walls.

2. A picker stick having its upper portion of wood and its lower portion of a single piece of sheet metal folded into channel form in cross section, the lower end of the wood extending but a short distance into the upper end of the channel, and a supporting member substantially U-shape in cross section inserted into the lower end of the channel to provide an extended bearing 120 for its pivot pin.

3. A picker stick having substantially its upper half of wood and substantially its lower half of sheet metal folded into channel shape, the lower end of the metal portion 130

being provided with spaced apart oppositely-disposed side walls and edge walls.

4. A picker stick having its upper portion of wood and its lower portion of sheet metal 5 folded into channel shape, the lower end of the metal portion being provided with spaced apart oppositely-disposed side walls and edge walls, said side walls being pierced to receive a pivot pin.
- 10 5. A picker stick having its upper portion of wood and its lower portion of sheet metal folded into channel shape, the lower end of the metal portion being provided with spaced apart oppositely-disposed side walls 15 pierced to receive the pivot pin, said walls about the pierced openings being turned inwardly to provide extending bearings for the pin.

6. A picker stick having its upper portion 20 of wood and its lower portion of sheet metal channel-shaped in cross section, its upper

end closely embracing the lower end of said wood, a member secured in said channel member near its lower end to provide a short length of opposite side wall, both of 25 said walls being pierced and having portions extending inwardly about the piercings to provide an extended bearing for a pivot pin.

7. A picker stick having its upper portion 30 of wood and its lower portion of sheet metal folded into channel shape, the lower end of the wood fitting closely into the channel, and a short section of channel member secured in said main channel member adjacent its lower end to provide spaced apart 35 side bearing walls.

In testimony whereof we affix our signatures.

DANIEL A. KEATING.
JAMES B. TATEM.
